METHOD AND APPARATUS FOR HYDROLYZING FATS AND OILS

Warren Davey, Montclair, and Martin Hill Ittner, Jersey City, N. J., assignors to Colgate-Palmolive-Peet Company, Jersey City, N. J., a corporation of Delaware

Application August 26, 1939, Serial No. 292,056

13 Claims. (Cl. 260—415)

This invention relates to a process and apparatus for hydrolyzing fats and oils. It relates more particularly to an improvement on countercurrent hydrolysis processes such as are disclosed and described in U. S. Patent No. 2,139,589 to Martin H. Ittner and U. S. Patent No. 2,156,863 to Victor Mills, and the concurrent-countercurrent process disclosed in U. S. Patent No. 2,221,799 to Martin H. Ittner.

An object of this invention is to conserve and utilize the heat in the fatty acid mixture and glycerine-water mixture produced, thus lessening the cost of production. Another object is to produce relatively pure, substantially unoxidized fatty acids and a glycerine-water mixture of high glycerine content.

In the Ittner process, fatty materials and water are treated in a vertical pressure vessel at relatively high temperatures and at pressures which exceed the pressure of saturated steam at the reaction temperature employed.

Both the fatty acids containing dissolved water and the glycerine-water produced are discharged from the pressure vessel at the pressure and temperature of operation and contain a considerable amount of sensible heat. In any process involving hydrolysis of fats and oils care must be taken that the fatty acids at high temperatures are not exposed to air or a material darkening will result, thus rendering them less desirable for use.

This sensible heat is available for many useful purposes if properly controlled and suitable means provided to take advantage thereof. A portion of the heat may be recovered by the use of heat exchangers, for example, to preheat the reactants. Alternatively, the outgoing materials may be "flashed," thus evaporating part of the water content. However, since all of the liquids passing through the heat exchangers are under relatively high pressures (which may be in the order of 600 pounds per square inch, or over), the heat exchangers must be designed to withstand high pressures. Furthermore, the heat exchangers are preferably made of corrosion resistant alloys, due to the corrosive nature of the materials. Under the most favorable conditions of operation, the heat thus recovered will probably not exceed seventy per cent of the heat available, and the glycerine-water mixture will leave the heat exchangers at the same concentration at which it entered, thus effecting no economy in the heat that will be required to concentrate the glycerine.

It has now been found that in a majority of cases there is enough sensible heat in the outgoing fatty acids and glycerine-water mixtures, if employed according to the principles of this invention, to not only vaporize practically all of the water in the glycerine-water mixture to yield glycerine of high concentration, but also to supply steam of various pressures which may be employed for preheating the incoming fatty materials and water to substantially high temperatures, for operating a vacuum ejector apparatus for maintaining a diminished pressure in an evaporator or glycerine concentrator, and for various other uses.

It is preferable to "flash" the glycerine-water mixture to a pressure and temperature well below the point at which glycerine will appreciably volatilize, and then concentrate the glycerine under a diminished pressure and at a correspondingly low temperature.

A preferred arrangement of an apparatus to carry out this process is shown in Fig. 1, although it will be clear to anyone understanding this invention and who is conversant with the art that this arrangement, and the type and number of units employed, may be varied in innumerable ways.

Referring to Fig. 1, 1 is a supply tank for water, preferably distilled or treated to remove impurities, 2 is a supply tank for oil or fatty material, also preferably treated for the removal of impurities.

The water is fed through pipe 3 to heat exchanger 4, thence through pipe 5 to pump 6.

Oil or fatty material is fed through pipe 7 to heat exchanger 8, thence through pipe 9 to pump 6.

Pump 6 is preferably a duplex single-acting pump of the plunger type, provided with a variable speed drive and a separate device on each cylinder to vary the length of the stroke, so that any amounts of water and fatty material may be pumped in proper proportions, with intermittent or alternate discharge, although any type of pump or pressure producing mechanism may be employed.

Pump 6 discharges water through pipe 10 and fatty materials through pipe 11.

Pipe 10 leads to a high temperature heater 12 and discharges through pipe 13 into the upper portion of the pressure reaction vessel 14.

Pipe 11 leads to a high temperature heater 15 and discharges through pipe 16 into the lower portion of the pressure reaction vessel 14.

The hydrolysis of the fatty material takes place in pressure vessel 14 forming fatty acids containing dissolved water and a glycerine-water solution.

A preferred type of pressure vessel consists of a high-vertical, carbon steel, pressure-resistant shell clad with a thin layer of corrosion resistant material, having relatively the same coefficient of expansion as the carbon steel, and an inner reaction chamber made from highly corrosion-resistant material free to move in relation to the outer shell, the pressure around and within the inner chamber being equalized by introducing steam in the surrounding space.

The fatty acid mixture is discharged from pressure vessel 14 through pipe 17 and the glycerine-water mixture is discharged from pressure vessel 14 through pipe 18.

Vessel 19 is a pressure boiler fitted with closed heating coils 20.

The fatty acid mixture is passed through coils 20 under pressure, entering at the temperature at which it leaves the reaction pressure vessel 14.

Water is supplied to boiler 19 through pipe 21 and a considerable portion of the sensible heat in the fatty acid mixture is absorbed in evaporating this water into steam.

Suitable control valves (not shown) regulate the flow of water into boiler 19 and steam therefrom.

A portion of the steam thus generated is passed through pipe 22 to a vacuum ejector 23, and the balance is passed through pipe 24 to oil heat exchanger 8.

The condensate passes out of heater 8 through pipe 25 and trap 26. A drainage connection 27 may be provided for emptying boiler 19.

The partially cooled mixture of fatty acids and water is now led through pipe 28 and is passed through closed coils 29 in another similar boiler 30.

The glycerine-water solution discharged from pressure vessel 14 through pipe 18 is passed through a suitable relief valve 31 and allowed to "flash" into boiler 30.

Another considerable portion of the sensible heat in the fatty acids-water mixture is absorbed in evaporating some of the water from the glycerine-water solution fed to boiler 30. Steam thus generated together with steam liberated by flashing is discharged through pipe 32. Suitable control valves (not shown) are provided for regulating the pressure and flow through boiler 30.

A drainage connection 33 may be provided for emptying boiler 30.

The fatty acids-water mixture is led through pipe 34 and passed through closed coils 35 to evaporator 36.

The partially concentrated glycerine-water solution leaving boiler 30 is passed through pipe 37 and allowed to flash into evaporator 36.

Another considerable portion of the sensible heat in the fatty acids-water mixture is absorbed in evaporator 36 in further evaporation of some of the water from the glycerine-water solution fed from boiler 30.

A portion of the steam discharged from boiler 30 through pipe 32 is led through pipe 38 and closed heating coils 39 in evaporator 36. The condensate from coils 39 passes out through pipe 40 and trap 41.

Evaporator 36 may be of the cascade type (a more detailed description of which appears hereinafter), and is maintained at a diminished pressure by means of a vacuum ejector 23 above re-

ferred to, and the vapor released from the glycerine-water solution as "flash" steam, as well as vapors generated by the absorption of heat from coils 35 and 39, discharges through pipe 42 into barometric condenser 43, and any air or non-condensable vapors are removed by vacuum ejector 23.

Furthermore, a portion of the steam generated in boiler 30 and discharged through pipe 32 is passed through pipe 44 into water heat exchanger 4. The condensate from this steam passes out of heat exchanger 4, through pipe 45 and trap 46. The cooled fatty acids-water mixture still under pressure is now passed through pipe 47 and a suitable relief valve 48 into receiving tank 49.

The concentrated glycerine-water mixture is drawn off through valves 50, 51 and 52 and receivers 53 and 54 into receiving tank 55.

A drainage connection 56 may be provided for emptying evaporator 36.

Suitable control valves (not shown) are provided for the water level, pressure, etc. in evaporator 36.

High pressure boiler 57 supplies steam for heating the water in heater 12 and the fatty material in heater 15 up to the desired temperature.

The steam is passed up through pipes 58 and 59, and the condensate is returned to boiler 57 through pipe 60.

Steam from boiler 57 is also supplied to pressure vessel 14 through pipe 61, and any condensate may be removed through trap 62, or returned to boiler 57.

The above description is, in general, a diagrammatic disclosure of the process of this invention.

In order to present a more thorough understanding of the process, a specific example of its operation is given. Quantities and proportions of fatty materials and water and glycerine, as well as temperatures and pressures, are taken from data obtained from actual operations.

It will be clear that there may be an almost unlimited number of combinations of quantities and temperatures and pressures, and results will vary depending on the operating conditions selected, namely, as to the pressures and temperatures in the various units and the amount of heating surfaces supplied to effect the final result. In any event, the fundamental principle may be better illustrated by the following example:

Quantities fed:

Fatty material (glycerides)	lbs. per hour	5000
Water	do	3000
Reaction temperature	244° C. (471° F.)	

Yields:

	Pounds
Fatty acids	4773
Water dissolved or mixed with fatty acids	850
Glycerine	550
Water in glycerine solution (23% glycerine concentration)	1827

The heat added to the pressure reaction vessel per hour is about 1,362,000 B. t. u. in 5,000 pounds of the fatty materials and about 1,362,000 B. t. u. in 3,000 pounds of water fed, a total of approximately 2,724,000 B. t. u. per hour. The heat in the materials removed from the pressure reaction vessel per hour is about 1,747,900 B. t. u. in 5,623 pounds of the fatty acids-water mixture and about 974,400 B. t. u. in 2,377 pounds of the glycerine-water solution, a total of approximately 2,722,300 B. t. u. per hour. Thus it will be seen

that neglecting radiation losses, the heat removed is substantially equivalent to the heat introduced, within the limits of errors of observation and operation. Any radiation loss is compensated for by the condensation of some of the steam surrounding the inner reaction vessel which does not enter in to the above calculations.

In this example, boilers 19 and 30 and evaporator 36 operate respectively at—

Pounds per square inch (absolute) -----	105	10
Pounds per square inch (absolute) -----	35	15
Pounds per square inch (absolute) -----	3	15

The fatty acids-water mixture leaves the pressure reaction vessel at about 471° F. and leaves coils 20, 29 and 35 at temperatures of about 344° F., 286° F. and 170° F., respectively.

Water fed to boiler 19 is taken at an initial temperature of 160° F. The drop in temperature of the fatty acids-water mixture in coils 20, from about 471° F. to 344° F., will give up approximately 534,000 B. t. u. which, when applied to the water fed into boiler 19, will vaporize about 500 pounds and convert it into 500 pounds of steam per hour at 105 pounds absolute pressure. Vacuum ejector 23 will require about 125 pounds of impelling steam per hour. This leaves 375 pounds of steam for use in heater 8. The available latent heat in this steam is about 332,000 B. t. u. per hour. The fatty material in supply tank 2 is taken at an initial temperature of 140° F. If the above 332,000 B. t. u. are applied to 5,000 pounds of fat introduced in heater 8 at 140° F., the temperature will be raised to 250° F.

To further heat the fatty material from 250° F. to 471° F. will require about 706,000 B. t. u. which will be supplied by high pressure steam from boiler 57.

The glycerine-water solution at 471° F., passing through relief valve 34 into boiler 30, will partially flash into steam and thus become more concentrated. The boiling point of pure water at 35 pounds absolute is 259.3° F. However, the glycerine-water solution will boil at a slightly higher temperature or in the neighborhood of 266° F.

The amount of "flash" steam thus liberated due to the reduction in pressure and temperature of the glycerine-water solution will amount to about 505 pounds. The fatty acids-water mixture entering coils 29 in boiler 30 at 344° F. and leaving at 286° F. will give up approximately 231,000 B. t. u. which, when applied to the glycerine-water solution in boiler 30, will further evaporate about 246 pounds of the water and convert it into an equivalent amount of steam at 35 pounds absolute. The "flash" steam amounting to 505 pounds plus the additional generated steam amounting to 246 pounds make a total of 751 pounds of steam discharged from boiler 30, its evaporation thus leaving 1,076 pounds of water together with 550 pounds of glycerine in the glycerine-water solution, a concentration of a little over 33% glycerine.

The solution now at about 266° F. passing into evaporator 36 operating under diminished pressure will again partially "flash" into steam and become further concentrated. The boiling point of pure water at 3 pounds absolute, the pressure in evaporator 36, is 141.5° F. However, the glycerine-water solution will boil at a slightly higher temperature or in the neighborhood of 145° F. The amount of "flash" steam thus liberated due to the further reduction in pressure and temperature of the glycerine-water solution amounts

to about 168 pounds. The fatty acids-water mixture entering coils 35 in evaporator 36 at 286° F. and leaving at 170° F. will give up approximately 452,000 B. t. u. which, when applied to the glycerine-water solution, will further evaporate about 433 pounds of the water therefrom and convert it into an equivalent amount of steam at 3 pounds absolute.

The flash steam amounting to 168 pounds plus the additional generated steam amounting to 433 pounds make a total of 601 pounds, its evaporation thus leaving 475 pounds of water together with 550 pounds of glycerine in the glycerine-water solution, a concentration of about 54% glycerine.

In order to still further concentrate the glycerine solution to obtain a desirable concentration of about 94% it will be necessary to remove therefrom a further quantity of water, about 440 pounds. Concentrated glycerine solutions boil at considerably higher temperatures than water, the boiling point of the above concentrated glycerine being in the neighborhood of 220° F. It will require approximately 461,000 B. t. u. to remove 440 pounds of water from this solution. Steam from boiler 30 at 35 pounds absolute and at 259° F. is passed through coils 39 in evaporator 36, and it will require about 490 pounds thereof to heat the glycerine-water solution to 220° F. and evaporate 440 pounds of water and convert it into steam at 3 pounds absolute. The total steam discharged from boiler 30 was found to be 751 pounds. This leaves 261 pounds of steam from boiler 30 at 35 pounds absolute available for heating the water passing through heat exchanger 4.

The latent or available heat in this steam is about 245,000 B. t. u. per hour. The water in supply tank 1 is taken at an initial temperature of 100° F. The above 245,000 B. t. u. applied to 3,000 pounds of water introduced in heater 4 at 100° F. will raise the temperature thereof to about 180° F. To further heat this water from 180° F. to 471° F. will require about 913,000 B. t. u., which will be supplied by high pressure steam from boiler 57.

Radiation losses from the pressure reaction vessel may be taken at 66,200 B. t. u. per hour. However, no radiation losses have been taken into account in the above calculations.

The total heat furnished by boiler 57 will, therefore, be—

B. t. u. for heating the fatty material -----	706,000
B. t. u. for heating the water -----	913,000
B. t. u. for radiation loss -----	66,200

B. t. u. per hour or approximately	
1,700,000 -----	1,685,200

The figure 1,700,000 B. t. u. per hour represents all of the heat required for hydrolyzing 5000 pounds of fatty material to 4773 pounds of fatty acid and 550 pounds of glycerine and evaporating the glycerine solution to 94% concentration.

It is also well within the scope of this invention to further recover considerable additional heat from traps 26, 41 and 46, or to re-use all or a part of the condensate from these traps in the process.

Of the 3000 pounds of water fed, about 323 pounds is absorbed chemically in the process and 2677 pounds is accounted for as 850 pounds of dissolved or mixed water with the fatty acids and 1827 pounds of water in the glycerine solution.

It is advantageous to use in the process a "cascade" evaporator or one which is constructed in stages so that liquids and vapors passing therethrough are successively at higher temperatures or vice versa.

Figs. 2, 3, and 4 show a type of a so-called "cascade" evaporator, Fig. 3 being an end view and Figs. 2 and 4 horizontal and vertical sections, respectively.

The glycerine-water solution entering the evaporator through pipe 37 will flash at a comparatively low temperature in the pan in the upper section.

Since it is desired to cool the fatty acids-water mixture to as low a temperature as possible, it is introduced through coils 35, where the glycerine-water solution is coolest and the temperature differential between them is greatest.

As the temperature of the glycerine-water solution increases materially as the concentration increases, steam from boiler 30 under a pressure of 35 pounds absolute and having a temperature of about 259° F. may be used in coils 39 in the section of evaporator 36 where the glycerine-water solution has become more concentrated and a higher temperature is necessary for its vaporization.

The final concentration of the glycerine-water solution may, of course, be accomplished in one or more vessels, but the advantages of using a "cascade" evaporator arranged as shown will become evident.

It is, of course, to be understood that all of the above temperatures and quantities of steam and vapor and concentration of glycerine solution produced may be varied considerably due to the exact arrangement of the apparatus employed and the amount of heating surfaces supplied in the several units; furthermore, an almost unlimited number of combinations may be evolved by changing the pressures on the various pieces of apparatus or by using more or fewer units, aiming, however, to accomplish the same results. The water content of the outgoing fatty acids and of the glycerine-water solutions varies with the kind and amount of fatty materials introduced, and the reaction pressure and temperature employed as well as with the proportion of fat and water used. The example given is clearly one of many similar or related possible arrangements, all of which embody the principles of this invention, to accomplish the desired results and is simply given to show the principle of the process involved.

We claim:

1. The process of producing fatty acids and concentrated glycerine which comprises hydrolyzing fats or oils under superatmospheric pressure and at an elevated temperature, separately removing fatty acids containing some dissolved water and a glycerine-water solution from the hydrolyzing chamber, utilizing a portion of the heat in the fatty acid-water mixture to generate steam under pressure, preheating the oil or fat before introduction into the hydrolyzing chamber with at least a portion of the steam so generated, employing a portion of said steam for producing a vacuum, flashing the glycerine-water solution to evaporate a portion of the water therefrom as steam under pressure, utilizing a further portion of the heat in the outgoing fatty acids-water mixture to further evaporate water from the glycerine-water solution as steam under pressure, preheating the water before introduction into the hydrolyzing

chamber with a portion of the steam generated from the glycerine-water solution, utilizing another portion of the steam thus generated to further evaporate water from the concentrated

5 glycerine-water solution at a lower pressure, flashing the partially concentrated glycerine-water solution to evaporate a portion of the water therein, and using a portion of the heat remaining in the fatty acids-water mixture to further evaporate water from the concentrated glycerine-water solution at the lower pressure, the evaporation of water from the concentrated glycerine solution being further assisted by reducing the pressure thereon below atmospheric.

10 2. The process of recovering heat obtained by splitting glycerine esters of fatty acids which comprises passing the split fatty acids under pressure in indirect heat exchange relation with water to generate steam, then passing said acids

20 in indirect heat exchange relation with the glycerine-water obtained from the splitting, which glycerine-water has been flashed to a lower but still elevated pressure in order to generate steam and to concentrate the glycerine, then passing

25 said fatty acids in indirect heat exchange relation with the concentrated glycerine from the second stage but at a reduced pressure in order to generate additional steam and to yield a highly concentrated glycerine; the steam from the first stage of heat exchange being partially used for reducing the pressure by ejection and condensation for the third stage of heat exchange, a part of the steam from the second stage of heat exchange being used for partially preheating

35 one of the reactants for splitting, and the other part of the steam from the second stage of heat exchange being used for vaporizing water from the glycerine in the third stage of heat exchange by passing it in indirect heat exchange relation therewith; the steam from the third stage of heat exchange being condensed under vacuum generated by part of the steam from the first stage of heat exchange.

40 3. The process of producing fatty acids and a concentrated glycerine solution which comprises contacting glycerides of fatty acids and water by countercurrent flow at superatmospheric pressure and elevated temperature, separately removing the fatty acids and glycerine solution from the hydrolysis chamber, reducing the pressure upon the glycerine solution to permit the evaporation of some of the water from the glycerine-water solution, and bringing the fatty acids into indirect contact with the glycerine-water solution to further the evaporation of water therefrom.

45 4. The process of claim 3 in which the fatty acids are not exposed to air until the temperature of said fatty acids has been substantially reduced.

50 5. The process of claim 3 in which the pressure upon the glycerine-water solution is reduced by stages, each reduction in pressure resulting in the removal by evaporation of some of the water, the evaporation of the water in at least one of the stages being promoted by heating the glycerine-water solution by indirect contact with the fatty acids produced in the hydrolysis.

55 6. The process of recovering heat from fat-splitting which comprises passing the fatty acids in indirect heat exchange relation with water and glycerine-water to concentrate the glycerine and to generate steam, passing parts of the steam generated from such indirect heat exchange in

indirect heat exchange relation with the reactants to partially preheat them.

7. The process of recovering heat from fat-splitting which comprises passing the fatty acids in indirect heat exchange relation with water and glycerine-water to concentrate the glycerine and to generate steam, passing parts of the steam generated from such indirect heat exchange in indirect heat exchange relation with the reactants to partially preheat them, and ejecting a part of said steam at a high velocity to reduce the pressure on the glycerine in at least one stage of concentration thereof.

8. The process of concentrating glycerine from fat-splitting which comprises flashing the glycerine-water solution and further concentrating the glycerine by utilizing the heat in the fatty acids by indirect heat exchange.

9. The process of producing substantially un-oxidized fatty acids and concentrated glycerine which comprises hydrolyzing fatty acid esters of glycerol under superatmospheric pressure and elevated temperature in the presence of water, flashing the glycerine-water solution produced by said hydrolysis and heating the glycerine-water solution by indirect contact with the fatty acids produced in said hydrolysis to concentrate the glycerine solution.

10. The process of producing fatty acids and concentrated glycerine which comprises hydrolyzing fats or oils under superatmospheric pressure and elevated temperature in the presence of water and utilizing at least a portion of the heat contained in the fatty acids to concentrate the glycerine-water solution by evaporating a portion of the water therefrom.

11. An apparatus for hydrolyzing fats and oils and producing fatty acids and concentrated glycerine which comprises, in combination with a

pressure hydrolysis vessel, means for separately withdrawing fatty acids and glycerine solution therefrom, means for reducing the pressure on the glycerine solution, means for bringing the steam thus generated into indirect contact with the water feed to preheat it, means for bringing the fatty acids into indirect heat exchange relation with water to generate steam, means for bringing steam thus generated into indirect contact with the fat or oil feed, means for bringing the fatty acids into indirect heat relation with the glycerine-water solution, and means for further reducing the pressure on the concentrated glycerine solution to evaporate more water therefrom.

12. An apparatus for hydrolyzing fats and oils and producing fatty acids and concentrated glycerine which comprises a pressure hydrolysis vessel, means for separately withdrawing fatty acids and glycerine solution from the hydrolysis vessel, and means for bringing the fatty acids into indirect heat relation with the glycerine solution while the glycerine solution is under a pressure lower than that in the hydrolysis vessel to evaporate a portion of the water from said glycerine solution.

13. An apparatus for hydrolyzing fats and oils and producing fatty acids and concentrated glycerine which comprises a pressure hydrolysis vessel, means for separately removing glycerine solution and fatty acids therefrom, means for reducing the pressure on the glycerine solution to volatilize water therefrom, and means for passing the fatty acids in indirect heat exchange with the glycerine-water solution to further concentrate the glycerine.
